WINDOW CONSTRUCTION (WIDTHWISE ADJUSTABLE SASH)

Roy T. Axe, Syracuse, N. Y., assignor, by mesne assignments, to The Syracuse Trust Company, Syracuse, N. Y., a corporation of New York, trustee

Application May 18, 1931. Serial No. 538,148

9 Claims. (Cl. 189—72)

This invention relates to window frame and sash constructions, particularly for railway cars and motor busses and the like and has for its object a particularly simple and efficient means for adjusting the sash to variations in the spacings and alignments of the posts of window framing constructions.

The invention consists in the novel features and in the combinations and constructions hereinafter set forth and claimed.

This application is a continuation in part of my application Ser. No. 431,579 filed February 26, 1930.

In describing this invention, reference is had to the accompanying drawing in which like characters designate corresponding parts in all the views.

Figure 1 is a fragmentary elevation of a window frame and sash embodying this invention.

Figure 2 is an inner face view of one of the elements by which the sash is adjustable in a widthwise direction.

Figure 3 is a sectional view on line 3—3, Figure 1.

Figure 4 is an enlarged fragmentary sectional view similar to Figure 3 of a modified form of this invention.

This window construction comprises, generally a post member having sash guiding means, a sash member coacting with the post and sash guiding means, one of said members being provided with an adjustable element fixed thereto for coacting with the other and adjustable in a direction widthwise of the sash so as to fit the sash to variations in the widthwise spacings of the posts and also to slight inclinations of the post out of the vertical, when the posts are slightly out of parallelism. The car or bus bodies are manufactured by one manufacturer while the standard window sashes are furnished by another manufacturer and fitted to the car body.

In building the car body, variations and inaccuracies are bound to occur, nevertheless the standard sashes must fit fairly accurate between the posts of the car body and the sash guiding means thereon and the object of this invention is to provide quickly adjustable means by which the car building can readily make the sashes conform to the slight variations that occur in the spacing and alignment of the posts.

In the illustrated embodiment of my invention, the adjustable element is carried by the sash and furnished as a unit with the sash by the sash manufacturer.

1 designates one of the post members and 2

the sash member. The post itself may be of any suitable form, size and construction and the sash guiding means thereof is here shown comprising outer and inner stops 3, 4.

The adjustable element 6 is mounted at the edge of the sash 2 and adjustable toward and from said edge and a weather strip 7 is carried thereby which engages the outer stop 3 and the element 6 is provided with means coacting with the sash to secure the same thereto. In the illustrated embodiment of my invention, this element 6 is in the form of a channel, the side walls of which embrace the front and rear walls of the sash 2, and these side flanges are tensioned to press or grip the sash.

In order to prevent inward displacement of the element 6 when it is adjusted so that the bottom of its channel formation is spaced apart from the edge of the sash, spacer or filler means are provided, here shown as inserts or shims 8. In order to further secure the element 6 to the sash, additional means are provided, here shown as studs 9 projecting into the channel from the bottom thereof and through holes 10 in the edge of the sash and the spacers or fillers 8 are provided with openings or perforations for receiving the studs, said openings having contracted slot-like entrances 11 which open through an edge of the fillers. The fillers are placed on the posts by sliding them around the posts so that the posts pass through the contracted entrances, the contracted entrances expanding while the post is passing therethrough and then contracting behind the post so that the spacers will not become dislodged but may be readily removed and replaced when force is intentionally applied to them to slide them laterally relatively to the posts.

In Figure 4, the frame is shown as formed with an offset 5 in the outer stop and the weather strip as projecting beyond the outer face into the offset 5 and engaging the bottom thereof. The sash is usually formed of sheet metal and the adjustable channel shaped element, the weather strip, offset 5 and the post structure are substantially as shown in my pending application Ser. No. 375,133 filed July 1, 1929, except that in application Ser. No. 375,133 the channel shaped element is not adjustable widthwise. The sash may be provided with latches 12 as in said application Ser. No. 431,579.

The invention of this application relates primarily to the widthwise adjustable feature and this feature is a continuation in part of the ap-

lication Ser. No. 431,579. It further relates to the filler or spacer feature.

In operation, the car builder can adjust the sash to variations in the spacing of the posts or 5 inclination of the posts by inserting fillers between each edge of the sash and the adjacent adjustable element, or between but one edge of the sash and the adjacent adjustable element and may adjust said element to conform to slight variations of the post by putting a certain number 10 of fillers around some of the pins and a less number around others, that is, if the post inclines or leans inwardly toward the center of the window opening from the bottom toward the top 15 of the posts, a filler may be inserted around the pins near the bottom and none around the pins at the top or more may be inserted around the pin at the bottom than around the pin at the top. Other arrangements of the filler to suit particular conditions can be readily imagined. 20

This invention is particularly advantageous in that it provides a particularly simple, efficient and economical way of adjusting standard sashes to variations in the spacing and alignment of the 25 posts of a window structure.

What I claim is:

1. In a window construction, the combination 30 of a window frame including a post having sash guiding means, a sash coacting with the post and slidably relatively thereto during raising and lowering of the sash, the sash being provided with an element at its edge for slidably coacting with the sash guiding means, said element being adjustable in a direction widthwise of the sash, and 35 means for holding said element from shifting in a widthwise direction when in its adjusted position during raising and lowering of the sash.

2. In a window construction, the combination 40 of a window frame including a post member having sash guiding means, a sash coacting with the post member and slidably relatively thereto during raising and lowering of the sash, the sash being provided with an element at its margin for slidably coacting with the post guiding means, 45 said element being adjustable in a direction widthwise of the sash, and comprising a body in the form of a channel slidably fitting the margin of the sash and adjustable edgewise of the sash for adjusting the sash to variations in the spacing 50 of the posts, and means for holding said element from shifting in a widthwise direction when in its adjusted position during raising and lowering of the sash.

3. In a window construction, the combination 55 of a window frame including a post having sash guiding means, a sash coacting with the post and slidably along the same during raising and lowering of the sash, the sash being provided with an element at its margin for slidably coacting with the post and the guiding means thereof, said element being adjustable in a direction widthwise of the sash, and comprising a body in the form of a channel slidably fitting the margin of the sash and adjustable edgewise 60 of the sash for adjusting the sash to variations in the spacing of the posts, the sides of the channel being tensioned to grip the sash, and thereby frictionally holding said element from shifting movement in a widthwise direction during the 65 normal operation of the sash.

4. In a window construction, the combination 70 of a window frame including a post having sash guiding means thereon, a sash member coacting with the sash guiding means, the sash being provided with an element extending lengthwise of

its edge for coacting with the sash guiding means and adjustable toward and from the edge of the sash, said element having means coacting with the sash to secure the same thereto, and means for holding said element from widthwise shifting movement including removable spacing means insertable between the edge of the sash and said element. 80

5. In a window construction, the combination 85 of a window frame including a post having sash guiding means thereon, a sash member coacting with the sash guiding means, the sash being provided with an element extending lengthwise of its edge for coacting with the sash guiding means and adjustable toward and from the edge of the sash, said element having studs projecting therefrom and the sash being provided with openings 90 in its edge for slidably receiving the studs and means for holding said element from widthwise shifting movement including spacers between the edge of the sash and the opposing surface of said element. 95

6. In a window construction, the combination 100 of a window frame including a post having sash guiding means thereon, a sash member coacting with the sash guiding means, the sash being provided with an element extending lengthwise of its edge for coacting with the sash guiding means and adjustable toward and from the edge of the sash, said element having studs projecting therefrom and the sash being provided with openings 105 for slidably receiving the studs and means for holding said element from widthwise shifting movement including spacers between the edge of the sash and the opposing surface of said element, 110 said spacers having openings for receiving the studs.

7. In a window construction, the combination 115 of a window frame including a post having sash guiding means thereon, a sash member coacting with the sash guiding means, the sash being provided with an element extending lengthwise of its edge for coacting with the sash guiding means and adjustable toward and from the edge of the sash, said element having studs projecting therefrom and the sash being provided with openings 120 for slidably receiving the studs, and means for holding said element from widthwise shifting movement including spacers between the edge of the sash and the opposing surface of said element, 125 said spacers having openings for receiving the studs, said openings opening through an edge of the spacers and being formed with contracted entrances for the studs. 130

8. In a window construction, the combination 135 of a window frame including a post having sash guiding means thereon, a sash member coacting with the sash guiding means, the sash being provided with an element extending lengthwise of its edge for coacting with the sash guiding means and adjustable toward and from the edge of the sash, said element being in the form of a channel having its side walls embracing the margin of the sash, said element being also formed with 140 studs projecting into the channel from the bottom thereof and the sash being provided with openings for receiving the studs, and means for holding said element from shifting in a widthwise direction including spacers interposed between the edge of the sash and the bottom of the channel and having openings for receiving the studs. 145

9. The combination with a window sash, window posts, and inner and outer stops, of an ele- 150

ment carried at the side edge of the sash and
adjustable laterally edgewise of the sash for ad-
justing the sash to variations in the spacing of
the window posts apart from each other, and
5 means for holding said element from shifting
movement in a widthwise direction including
spring pressed flanges carried by said element,

whereby said member and the flanges form a
channel, said flanges being tensioned to snugly
grip the sash and hold said element from out-
ward displacement in the normal operation of
the sash.
